HUMIDIFIER

Earl L. Tornquist, Elmhurst, Ill.

Application May 27, 1935, Serial No. 23,553

12 Claims. (Cl. 126—350)

This invention relates to humidifiers, and especially to those designed for humidifying dwelling houses. An object of the invention is to provide a simple and inexpensive humidifier which is reliable in operation, is adapted for use with gaseous fuel, and which delivers a supply a water vapor in a dry or invisible form without condensation and without such a saturation that it tends to condense.

These objects are achieved, according to one phase of the invention, by heating water to a vapor by means of a burner, then mixing with the water vapor the hot products of combustion from the burner (also containing a considerable proportion of water vapor), and discharging the mixture of water vapor and products of combustion into the space to be humidified, as a substantially dry and invisible gas.

In one effective and simple arrangement, the burner discharges its products of combustion upwardly through a vertical passage through a container in which water vapor is formed by the heat of the burner, and the vapor so formed passes through openings into the upper end of the passage. The outer casing is provided with means for directing the mixture of water vapor and products of combustion into the space to be humidified.

The container in which the vapor is formed, the burner, the outer casing, and the controls all embody novel features of structure and arrangement which, with various other objects and features of the invention, will be apparent from the following description of the illustrative embodiment shown in the accompanying drawings, in which:

Figure 1 is a vertical section through the humidifier in a plane passing through the above-described vertical passage;

Figure 2 is a horizontal section therethrough on the line 2—2 of Figure 1;

Figure 3 is a vertical section therethrough on the line 3—3 of Figure 1, and with an automatic humidity control indicated diagrammatically;

Figures 4, 5, 6, 7, and 8 are perspective views of parts of the inner casing, the container, and the burner;

Figures 9 and 10 are plan views of the gaseous fuel burner, with a safety control device shown in two different positions in the two views;

Figure 11 is a perspective view of the complete humidifier;

Figure 12 is a vertical section through the outer casing;

Figure 13 is a perspective view of the body of the outer casing;

Figure 14 is a perspective view of the removable cover of the outer casing;

Figure 15 is a detail view showing the latching of the fuel valve when the burner is first lighted; and

Figure 16 is a similar view showing the latch released.

The humidifier selected for illustration comprises a base 10 of stamped steel, carrying an inner casing 12 (best shown in Figure 4), over which is secured an outer casing or housing 14 (Figures 11 to 14) having a removable angular cover 16 for its top and front. The cover 16 carries a grill 18 over the outlet of a discharge conduit 20 carried by, and opening downwardly through the center of, a cover 22 for the inner casing 12.

The cover 16 may have mounted thereon, if desired, a suitable humidity indicator 24 of any desired construction, and is shown formed with an opening 26 for the control knob 28 of a fuel valve described below. The top of the housing 14 may be reinforced by a strap 30 having an opening 32 aligned with the opening 26.

Suitable brackets carried by the inner casing 12 support a vertically arranged open-ended rectangular burner box 34 across which is arranged a burner element in the form of a pipe section 36 perforated on its upper side, and which receives gas fuel from a conduit 38 having a spring-closed plunger type valve 40 through which it communicates with a supply conduit 42 extending upwardly to an adjustable main control valve 44 operated by the knob 28, beyond which is a conduit 46.

In the arrangement illustrated, there is a bypass 48 (controlled by a suitable valve 50 which is inside the housing and which is seldom changed after once being set when first installed) around the valve 44. Thus the device is operated on a high-low cycle by opening and closing the valve 44.

The valve 40 is arranged to be held open, in normal operation, by a spring plunger 52 carried by the end of a bimetallic thermostat strip 54 secured to the burner box 34 where it will be heated by flame from the burner element 36. If the flame goes out, the thermostat 54 moves the plunger 52 back and allows the valve 40 to close. A pivoted member 56 can be swung to the position of Figure 10, to hold valve 40 open when the burner is first lighted, until the thermostat 54 heats up, whereupon the member or latch 56 drops

automatically back to the idle position shown in Figure 9.

If desired, in addition to or in place of the manually-operated valve 44, the humidifier may be provided with a high-low, electrically-operated valve 58 of any desired construction, controlled by a room humidostat 60 connected thereto by electric connections 62. This type of control is well known and is therefore not shown in detail.

The burner box 34 is shown as carrying a bracket or support 64 on which rests the lower end of a water container or boiler 66 which has its bottom recessed at 68 for the upper end of the burner box 34. The container 66 is supplied with water held at a predetermined level by means such as a float valve mechanism 70 of any desired construction. The float valve mechanism 70 is shown supported on the inner casing 12 by means such as a strap 72, and discharges into the container 66 through a coupling 74. Water reaches the float valve mechanism 70 through a filter 76 from a coupling box 78 which also contains the gas line connection.

The recessed space 68 of the container 66 communicates at its top with the lower end of a tube or flue 80 which forms a vertical passage arranged centrally of the container 66 and communicating therewith at its upper end through openings 82. The passage 80 discharges into the outlet member 20 described above.

In operation, the burner 36, under a high-low control (which may be the manual valve 44 or the automatic control 58-60), heats the water in container 66. The water vapor so formed passes through openings 82 and is mixed with the products of combustion from the burner, the mixture being discharged into the space to be humidified, through the outlet 20.

This not only serves to dilute and to superheat the vapor, preventing condensation and forming a dry gas, but the moving current of products of combustion or exhaust gases from the burner serves as a substitute for a fan or the like to mix the gases and discharge them with considerable force into the room, insuring a wide distribution thereof.

The humidifier may be provided with any desired safety devices, such as a low water cutoff 50 of a suitable mechanical or electrical type.

While one illustrative construction has been described in detail, it is not my intention to limit the scope of my invention to that particular construction, or otherwise than by the terms of the

55 appended claims.

I claim:

1. A humidifier comprising a casing containing a container for water, a burner arranged to heat the water in said container, fuel supply means 60 for the burner including two valves arranged in parallel and one of which has operating means within the casing and the other of which has operating means arranged exteriorly of the casing, and means for mixing vapor formed in said container with the products of combustion from the burner and discharging the mixture into the space to be humidified.

2. A humidifier comprising a casing containing a container, means for keeping water at a constant level therein, a burner below the container, means for supplying fuel to said burner and including two valves arranged in parallel and one of which has operating means within the casing and the other of which has an operating device 70 projecting through the upper part of the casing

to permit operation of said other valve from outside the casing, and means at the top of the container for mixing vapor from said container with the products of combustion, from said burner and discharging the mixture into the space 5 to be humidified.

3. A humidifier comprising a container having a central vertical passage therethrough, means for keeping water at a constant level therein, a burner below the container and discharging products of combustion into said passage, and said container having at its upper end openings into said passage for mixing vapor from said container with said products of combustion, and means for discharging the mixture into the space 10 to be humidified.

4. A humidifier comprising a burner, a container of water supported upon and above said burner and having a central vertical passage serving as a flue for said burner and having openings at its upper end discharging water vapor into said passage, and means for directing mixed water vapor and products of combustion from the upper end of said passage into the space 20 to be humidified.

5. A humidifier comprising a burner, a container above said burner and having a central vertical passage serving as a flue for said burner and having openings at its upper end discharging vapor into said passage, and means for directing 30 mixed water vapor and products of combustion from the upper end of said passage into the space to be humidified.

6. A humidifier comprising a burner, a container of water supported upon and above said 35 burner and having a central vertical passage serving as a flue for said burner and having openings at its upper end discharging water vapor into said passage, and means for directing mixed water vapor and products of combustion from 40 the upper end of said passage into the space to be humidified, said burner having an external bracket supporting the lower end of said container.

7. A humidifier comprising a burner, a container above said burner and having a central vertical passage serving as a flue for said burner and having openings at its upper end discharging vapor into said passage, and means for directing mixed water vapor and products of combustion 50 from the upper end of said passage into the space to be humidified, said humidifier having a control for the fuel of said burner mounted on the exterior of the humidifier.

8. A humidifier comprising a water container 55 having a space recessed into its bottom which continues upwardly as a passage vertically through the container and with openings from the container into the upper end of said passage, a burner box extending below the container 60 and seated at its upper end in said space, and an outer casing provided with means for discharging mixed water vapor and products of combustion received from the upper end of said passage.

9. A humidifier comprising a water container having a space recessed into its bottom which continues upwardly as a passage vertically through the container and with openings from the container into the upper end of said passage, 70 a vertically-arranged burner box extending below the container and seated at its upper end in said space, a loop-shaped horizontally-arranged gas burner in said box, and an outer casing 75 provided with means for discharging mixed

water vapor and products of combustion received from the upper end of said passage.

- 5 10. A humidifier comprising a water container having a space recessed into its bottom which continues upwardly as a passage vertically through the container and with openings from the container into the upper end of said passage, a vertically-arranged burner box extending below the container and seated at its upper end 10 in said space, a loop-shaped horizontally-arranged gas burner in said box, and an outer casing provided with means for discharging mixed water vapor and products of combustion received from the upper end of said passage, together with 15 thermostatic means in said burner box above said burner arranged to shut off the fuel supply if the burner goes out.
11. A humidifier comprising a base having mounted thereon an inner casing having a laterally-extending discharge conduit on its top, a water container supported within said inner casing, a burner arranged to heat the water in said container, said inner casing and said container
- 20

being constructed and arranged to discharge mixed water vapor and products of combustion into said discharge conduit, and an outer casing supported on said base and inclosing said inner casing and said container and said burner and having a removable part provided with an outlet opening registering with the end of the discharge conduit.

12. A humidifier comprising a base having mounted thereon an inner casing having a laterally-extending discharge conduit on its top, a water container supported within said inner casing, a burner arranged to heat the water in said container, said inner casing and said container being constructed and arranged to discharge mixed water vapor and products of combustion into said discharge conduit, and an outer casing supported on said base and inclosing said inner casing and said container and said burner and provided with an outlet opening reigstering with 20 the end of the discharge conduit.

E. L. TORNQUIST.
